CLAIM

I claim the ornamental design for a dual fishing lure, as shown and described.

DESCRIPTION

FIG. 1 is a perspective view of a dual fishing lure, showing my new design;

FIG. 2 is a top plan view thereof, the bottom plan view being a mirror image thereof;

FIG. 3 is a left-side elevational view thereof, the right side elevational view being a mirror image thereof;

FIG. 4 is a rear elevational view thereof; and,

FIG. 5 is a front elevational view thereof.
